METHOD OF PRODUCING PILE FABRIC

Arthur G. Holland, Bridgeport, Conn., assignor
to Sidney Blumenthal & Co. Inc., New York,
N. Y., a corporation of New York

Application February 8, 1935, Serial No. 5,588

4 Claims. (Cl. 139—391)

This invention relates to a method of producing a pile fabric, and particularly such a fabric in which the pile is composed of narrow strips of cellulosic material, such as cellophane, or the like.

An object of the invention is to provide such a fabric having a very attractive sparkling effect when viewed from any angle.

A further object is to provide a method of making and treating a cellophane pile fabric in order to interrupt the regular lines of pile so as to give the fabric a sparkling appearance.

A still further object consists in providing certain improvements in the form, construction and arrangement of the parts, in the materials employed, and in the steps followed, whereby the above named and other objects may effectively be attained.

Referring to the drawing:

Fig. 1 represents a perspective view of a pile fabric being treated in accordance with the present invention;

Fig. 2 represents a top plan view of a portion of the fabric, several times enlarged; and

Fig. 3 represents a vertical section taken along the line III—III of Fig. 2, looking in the direction of the arrows.

As illustrated herein, the fabric is made in accordance with the usual practice customarily followed in the manufacture of transparent velvets, the weave being the usual six pick arrangement. The backing threads comprise warp threads 1 and weft threads 2, the latter being disposed in groups of three, with a cellophane warp pile strip 3 looped around each three weft threads in the form of a W, as clearly shown in Fig. 3. In a pile fabric of the sort just described, the cellophane pile normally stands stiffly erect, so that a top view of the fabric reveals only relatively regular lines across the width of the fabric corresponding to the cut upper ends of the pile strips. Owing to the very small area of these cut ends, the fabric, as a whole, has a rather dull appearance.

In many cases it is desirable to take advantage of the natural shiny surface of the cellophane pile strips, and it has been found that the ends of certain pile strips may be permanently bent over to a position approaching parallelism with the back of the fabric. This bending over may be accomplished very readily by passing the cut pile fabric, in either finished or unfinished condition, beneath an ordinary fabric printing roll; the roll being of course, clean and free from any die or ink. A printing roll of this sort is indi-

cated at 4, Fig. 1, the engraved portions of the roll being shown at 5 and the high portion at 6; the fabric itself being designated by the numeral 7, and shown as being moved in the direction of the arrow. It has been found satisfactory to pass the fabric 7 beneath the roll 4 at ordinary room temperature and with no more pressure on the roll than is usual in the printing of colored designs on a fabric, which may be, for instance, merely the pressure resulting from the weight of the roll. The high part 6 of the roll acts to bend over certain irregularly disposed individual ends of the pile strips, in such a way that the bent over portions remain substantially in the position to which they are bent, as indicated at 8, and these bent over portions then present an appreciable flat surface area which gives an attractive sparkling effect to the fabric as a whole when viewed from any direction. In actual practice it is found that only certain ones of the pile strips which are opposite the raised part 6 of the roll are acted on in the manner just described, so that the sparkling appearance of the fabric seems to have little relation to the design engraved on the roll 4, but it is desirable that this design be relatively fine and irregular, in order to ensure the resulting irregularity in distribution of the bent over pile strips.

The backing threads 1 and 2 may desirably be composed of silk, but other materials, such as rayon or cotton or combinations of these materials might also be used if desired. The strips of cellophane, or the like, have generally a thickness of about .001 inch and may be of any desired width, a width of .016 inch having been found suitable, the pile having a height of approximately .07 inch, and the bent over portion constituting generally less than half the total height of the pile. The dimensions just given are intended to be illustrative only, since it will readily be appreciated that strips of cellophane, or the like, of different sizes could be treated in substantially the same way with the similar result. The fabric above described is of such a nature as to be useful particularly for the trimming of hats and dresses, but it retains its desirable characteristics sufficiently to make it useful in most of the places where ordinary transparent velvet might otherwise be used.

It will be understood that various changes may be resorted to in the form, construction and arrangement of the several parts, in the materials employed, and in the steps followed, without departing from the spirit and scope of my invention; and hence I do not intend to be limited to

the details herein shown and described, except as they may be included in the claims.

What I claim is:

1. The method of making a pile fabric which includes, providing a fabric having a cut cellophane pile and passing said fabric beneath a roll having high and low surface areas, whereby irregularly distributed individual piles are bent over toward parallelism with the plane of the fabric.
2. The method of making a pile fabric which includes, providing a fabric having a cut cellophane pile and passing said fabric beneath a roll having high and low surface areas, the pressure on the roll being no greater than that used in printing colored designs on a pile fabric, whereby irregularly distributed individual piles are bent over toward parallelism with the plane of the fabric.

3. The method of making a pile fabric which includes, providing a fabric having a cut cellophane pile and passing said fabric beneath a roll having high and low surface areas, the roll and fabric being at normal room temperature, whereby irregularly distributed individual piles are bent over toward parallelism with the plane of the fabric.

4. The method of making a pile fabric which includes, providing a fabric having a cut cellophane pile and passing said fabric beneath a roll having high and low surface areas, the pressure on the roll being no greater than that used in printing colored designs on a pile fabric and the roll and fabric being at normal room temperature, whereby irregularly distributed individual piles are bent over toward parallelism with the plane of the fabric.

ARTHUR G. HOLLAND.
